SHEET TRANSFER MECHANISM FOR
PRINTING PRESSES

Alexander T. Koppe, New York, N. Y.

Application November 29, 1933, Serial No. 700,258

51 Claims. (Cl. 271—53)

This invention relates to paper positioning mechanism for printing presses and its purpose is to provide improved means for moving paper sheets to the cylinders of a press and accurately 5 positioning them on a cylinder so that the subject-matter to be printed appears in identical positions on successive sheets. The principal object of the invention is to provide a new and improved form of positioning mechanism which receives the sheets from the feeding mechanism of 10 the press and moves these sheets successively to predetermined positions on a cylinder of the press. A further object of the invention is to provide improved paper positioning mechanism comprising a movable vacuum device with respect 15 to which each paper sheet is accurately positioned and by which it is moved to a position wherein its edge engages stops on a rotating cylinder of the press. A further object of the invention is to provide a vacuum feeding device comprising one 20 or more rotatable vacuum drums on which each paper sheet is accurately positioned and by which it is moved accurately against stops on a press cylinder. Still another object of the invention is 25 to provide paper positioning mechanism comprising a table on which the paper sheet is accurately positioned in combination with an extension shelf or plate extending between the body of said table and the cylinder against which the paper sheets 30 are moved in combination with a series of rotary vacuum drums adapted to engage the paper sheet or other stock on the shelf or plate and to advance the sheet positively toward the cylinder by the action of suction applied progressively 35 through the moving drums. A further object of the invention is to provide improved paper feeding means by which the sheet of paper or other stock is positively gripped at successive points by a suction feeding device and thereby positively 40 moved against the stops on the rotating cylinder, thus overcoming the disadvantages of prior devices in which the movement of the paper sheet has been effected merely by frictional contact with a feeding device. A further object of the 45 invention is to provide a paper supporting plate from which the paper sheet is picked up and advanced by rotary feeding devices in combination with means for adjusting the supporting plate to accommodate varying thicknesses of paper. A 50 further object of the invention is to provide improved means for adjusting successive sheets of paper or other stock upon a table preliminary to the movement of the sheets by feeding devices to the cylinders of the press. Other objects relate

to various features of construction and arrangement which will appear more fully hereinafter.

The nature of the invention will be understood from the following specification taken with the accompanying drawings, in which one embodiment is illustrated. In the drawings,

Fig. 1 shows a partial side elevation of an improved offset printing press embodying the features of the present invention;

Fig. 2 shows an enlarged horizontal section taken on the line 2—2 of Fig. 1, with parts thereof broken away;

Fig. 3 shows a vertical section taken on the line 3—3 of Fig. 1, illustrating, in end elevation, the principal features of the present improvement;

Fig. 4 shows an enlarged vertical section taken on the line 4—4 of Fig. 2, illustrating the stops and paper positioning devices in their elevated positions to permit the movement of a paper sheet by the vacuum feeding devices to the paper receiving cylinder of the press;

Fig. 5 shows a detail vertical section taken on the line 5—5 of Fig. 2;

Fig. 6 shows a partial sectional view similar 25 to that of Fig. 4, illustrating the relative positions of the parts when the paper stops and paper positioning devices are lowered preliminary to the movement of the sheet by the vacuum feeding devices;

Fig. 7 shows a vertical section taken on the line 7—7 of Fig. 2;

Fig. 8 shows an enlarged detail section taken on the line 8—8 of Fig. 7;

Fig. 9 shows a vertical section through the 35 vacuum feeding devices taken on the line 9—9 of Fig. 2;

Fig. 10 shows a detail vertical section taken on the line 10—10 of Fig. 9;

Fig. 11 shows an enlarged vertical section taken 40 on the line 11—11 of Fig. 9;

Fig. 12 shows an enlarged vertical section taken on the line 12—12 of Fig. 9;

Fig. 13 is a partial horizontal section on the line 45 13—13 of Fig. 3, with parts broken away, showing the means for positioning the paper sheet laterally on the table before it is picked up and moved by the vacuum feeding devices;

Fig. 14 is a perspective view of the actuating lever and associated parts embodied in the mechanism illustrated in Fig. 13; and

Fig. 15 is a vertical section taken on the line 15—15 of Fig. 13.

The invention is illustrated in the drawings as being embodied in a printing press adapted for 55

offset printing and this machine comprises a pair of side frames 20 which are secured to the base or other foundation upon which the printing press rests and which have rearward extensions 20^a 5 adapted to carry certain parts of the operating mechanism. The apparatus carried by these side frames is adapted to receive the sheets of paper or other stock, upon which the printed impressions are to be placed by the operation of the press, 10 over an inclined conveyor 21 which is adapted to receive the paper sheets 22 from a suitable paper feeding device such as that described and claimed in my co-pending application Serial No. 706,188, filed January 11, 1934. The conveyor 21 comprises an inclined feed board 23 having endless 15 tapes 24 moving over the surface thereof and around pulleys 25 which are carried by brackets 26. These endless tapes move in the direction of the arrow 27 for carrying the paper sheets 20 downwardly and moving them over the paper positioning table 30 which extends between the side frames of the press and which has a rearward extension or plate 30^a extending to and connected with the lower end of the feed board 23. The 25 table 30 also has a forward extension 30^b forming a sheet support which extends beneath a series of vacuum feeding drums 31 arranged in a row transversely of the press and adapted to rotate in the direction of the arrow 32. The plate 30 30^b is provided with notches 30^c in the edge thereof adjacent the drum 31 and these notches are 30^a adapted to receive stop members 33 which are adapted to engage the forward edge of the paper sheet 22 when it has been moved to a position 35 over the table 30. The stop members 33 are carried by arms 33^a which are adapted to have pivotal movement for elevating the stop members 33 to permit the paper sheet to be advanced by the rotation of the drums 31 which have periodic or 40 intermittent rotary movements, each movement being adapted to advance a paper sheet until it is engaged by the gripping means on the paper-carrying cylinder 34 of the press.

The stop members 33 in their elevated positions 45 are as illustrated in Fig. 4, thus permitting the movement of the paper sheet beneath the drums 31 until the sheet engages the stops 35 which are carried by the cylinder. The cylinder rotates in the direction of the arrow 36 and the speed of 50 movement of the paper sheet is preferably slightly greater than the peripheral speed of the cylinder so that the edge of each sheet is positively engaged by the stops 35. The paper sheet is guided in this movement against the stops by means of 55 guide fingers 37 which have upturned extremities 37^a located in proximity to the edge of the table extension 30^b. When the forward edge of the paper sheet 22 has been moved against the stops 35, as shown in Fig. 12, this edge of the sheet is 60 engaged and held by a series of grippers 38 which are pivotally mounted on the cylinder 34 and which are adapted to be automatically actuated to engage the paper sheet at the proper time. The paper sheet is then moved beneath the guide 65 fingers 37 and is carried around the cylinder 34 which may be provided with a draw sheet to underlie the paper sheet on the cylinder when perforating wheels are to be used. When positioned on the paper-carrying cylinder 34, the 70 paper sheet 22 is adapted to receive an impression from the transverse cylinder 40 which rotates in the direction of the arrow 41 and which is provided with a rubber blanket 42 adapted to receive its impression from an offset press plate 44, of 75 zinc or the like, which is mounted on the plate

cylinder 45. The press plate 44 is adapted to be inked by a series of ink rollers 46 which are mounted to revolve in bearings 47 carried by an ink receptacle 48 pivotally mounted on the upper ends of the side frames 20.

When a draw sheet is to be used with the usual perforating wheels, it is clamped at one edge between a bar 47 and a plate 48 in the recess 34^a of the paper carrying cylinder and the other edge of this draw sheet is clamped between the shoulder at one edge of another cylinder recess 34^b and the stop members 35 against which the paper sheets are positioned. These stop members 35 are carried by blocks 49 which may be clamped in position on a rod 50 extending longitudinally of the recess 34^b and having its ends secured to the end walls of the cylinder. The paper gripping fingers 38 are carried by brackets 51 which are clamped on a shaft 52 journaled in the ends of the cylinder 34 and having one of its ends projecting beyond the cylinder, as shown in Figs. 2 and 5. This projecting end of the shaft 52 has secured thereon a crank arm 53 carrying a roller 54 which is adapted to coact with stationary cams 55 carried by and projecting inwardly from one of the side frames 20. The shaft 52 also carries a crank arm 56 having a pivotal connection with a rod 57 which slidably engages a lug 58 projecting from the end of the cylinder. A coil spring 59 is mounted on the rod 57 between the lug 58 and a collar 60 which is secured on the rod so that the spring 59 tends to maintain the roller 54 in a position where it will engage the cams 55 during the rotation of the cylinder 34 and thus cause the shaft 52 to be moved angularly by the crank arm 53 for the purpose of elevating the gripping fingers 38 to receive the paper sheet. When the sheet has been positioned against the stops 33, the fingers 38 are returned to their gripping positions by the action of the coil spring 59 and the paper sheet is then securely held during the continued rotation of the cylinder until it is again released by engagement of the roller 54 with the lower cam 55. During this rotation of the cylinder 34, the paper sheet 22 receives an inked impression from the transfer cylinder 40 and the lower cam 55 then causes the forward edge of this sheet to be released in the lower part of its path of travel, at which time it is taken off by the delivery cylinder 60 which is mounted to revolve beneath the paper carrying cylinder. The delivery cylinder 60 is provided with a recess adapted to receive successive gripping units carried by an endless conveyor chain 64, each unit including a bar 61 adapted to be engaged by the edge of the sheet 22 and a series of gripping fingers 62 which are carried by a shaft 63 carried by the chain. Each shaft 63 is provided on one of its projecting ends with mechanism whereby the gripping fingers 62 are automatically actuated at a predetermined time during their travel around the cylinder 60. Each sheet 22 is thus gripped and carried away from the cylinder 60 by the endless conveyor chain 64 which transfers the paper sheet to suitable stacking mechanism, not forming a part of the present invention, by which the printed sheets are arranged accurately in a pile.

The cylinders 34, 40, 45 and 60 are driven by mechanism which is located adjacent one of the side frames 20, as shown in Fig. 1. This mechanism comprises a shaft 65 which is journaled in bearings in the side frames and which is provided with a pulley 66 adapted to be driven

through a belt 67 by an electric motor or the like. The shaft 65 is provided at one end with a sprocket gear 68 meshing with an endless sprocket chain 69 which extends upwardly and around a sprocket gear 70 secured upon a shaft 71 which also has bearings in the side frame members 20. The shaft 71 has fixed thereon a pinion 72 which meshes with a large gear 73 secured upon a shaft 74 having journals in the lower parts of the side frames. This shaft 74 has a bevel pinion 75 fixed on one end thereof to mesh with another bevel gear 76 which is fixed upon the lower end of a vertical shaft 77 having bearings in the brackets 78 which are secured to the adjacent side frame 20. At its upper end, this shaft 77 has a bevel pinion 79 fixed thereon to mesh with a bevel gear 80 which is secured upon the shaft 81 of the plate cylinder 45. The shaft 81, like the shafts of the other cylinders, is journaled in bearings carried by the side frames 20 and through the connection just described it is driven to revolve in contact with the transfer cylinder 40 and the inking rolls 46. On the inner side of one of the side frames 20, the shaft 81 of the plate cylinder has a gear 83 secured thereon to mesh with a similar gear 84 which is secured upon the shaft 85 of the transfer cylinder 40. This gear 84 also meshes with a gear 86 which is secured upon the shaft 87 of the paper carrying cylinder 34 so that the paper-carrying cylinder is driven from the transfer cylinder. The delivery cylinder 60 is fixed upon a shaft 90 which projects through bearings in the side frames 20 with one end thereof carrying a relatively fixed bevel gear 91 which is arranged to mesh with a driving pinion 92 secured upon the previously described vertical shaft 77. In this way, all of the cylinders are positively driven in timed relation to each other.

Referring now, in greater detail, to the mechanism by which the sheets are transferred from the conveyor 21 to the cylinder 34, it will be seen from an examination of Figs. 4, 6, 9, 10, 11 and 12 that the suction feeding drums 31, heretofore mentioned, are in the form of radial disks 31^a having transversely extending annular flanges 31^b at their outer edges. These disks have hubs 31^c which are secured by keys 94 upon a hollow shaft 95 which extends transversely of the machine, above the paper supporting plate 30^b, with the end portions thereof journaled in bearings which are formed in the side frames 20, as shown particularly in Fig. 9. The shaft 95 also has mounted thereon a series of suction blocks 97 each of which is associated with one of the drums 31. Each block 97 comprises an arm 97^a which extends vertically downward from the shaft 95 with a passage 97^b formed therein to communicate with the internal passage 95^a of the hollow shaft 95 through one of the ports 95^c which are formed in the shaft. The flange 31^b of each vacuum drum 31 is provided throughout a portion of its circumference with a series of spaced suction openings 31^d which are adapted to register successively with the suction passage 97^b as the drum is revolved about the associated block 97. The ports 97^b which are formed in the hollow shaft 95 are extended through a substantial arc, as shown in Figs. 11 and 12, corresponding to the arc through which the openings 31^d are distributed around the periphery of the drum so that as the drum revolves, a communication is established between the interior of the hollow shaft and each of the passages 97^b throughout the time that the openings 31^d are passing be-

neath the lower end of the suction block. The shaft 95 also carries a series of sleeves 98 which are mounted between adjacent members 31 and 97 on the shaft in order to space them apart. In addition to the downwardly extending arms 5 97^a, each suction block comprises a horizontally extending arm 97^c terminating in a hub portion 97^d which is engaged by a shaft 99 extending transversely of the press and having its ends journaled in brackets 100 carried by the side 10 frames 20, thus holding the suction blocks 97 against rotation while the drums 31 revolve about them. One end of the shaft 95 is closed by a plug 101 and the other end is connected to a source of suction, as hereinafter described, so that a partial vacuum is maintained within the hollow shaft 95 and as the shaft is rotated by the mechanism hereinafter referred to, the suction acting through the passages 97^b and the openings 31^d operates to pick up the paper sheet 22 from 20 the supporting plate 30^b and move it in the direction of the cylinder 34 as the drums rotate. The distribution of the openings 31^d about a portion of the periphery of each drum 31 is such that while the last opening is passing beneath a passage 97^b, as the drums rotate in the direction of the arrow 102, in Figs. 11 and 12, the forward edge of the sheet will have engaged the stops 35 carried by the cylinder 34, and the paper sheet is then gripped by the fingers 38, as shown by 30 dotted lines in Fig. 12, just before the sheet is released by the suction applied through the last openings in the drums 31.

The mechanism for rotating the shaft 95 is adapted to produce a complete rotation of the 35 shaft during the movement of each paper sheet 22 over the table 30 and at the end of each rotation, the shaft and the drums 31 come to a complete stop and remain stationary until the next paper sheet is moved into engagement with 40 the stop members 33. In order to insure the stopping of the shaft 95 and the connected drums 31 at the end of each revolution, without any overrunning due to momentum, the shaft 95 is 45 provided with a brake comprising a brake drum 104 secured upon one end of the shaft by means of a key 105, as shown in Fig. 9, and engaged by a brake strap comprising complementary members 106, each partially surrounding and engaging the annular groove of the brake drum, as 50 shown in Fig. 7. These complementary brake strap members 106 are each provided with bifurcated extremities 106^a which are adapted to rock upon a supporting rod or pin 107 projecting outwardly from the adjacent side frame 20 and they 55 are secured together in engagement with the brake drum by means of a stud 108 passing through apertures in the upper member and threadedly engaging holes in the lower member. This stud has a coil spring 109 mounted on the 60 projecting portion thereof. The head 111 of the stud is provided with a groove for engagement by a screw driver and a washer 110 seated against the head is engaged by one end of the spring 109. By the adjustment of this stud, the compression of the spring 109 may be regulated to 65 vary the pressure with which the strap members 106 engage the brake drum.

The drums 31 are spaced apart longitudinally of the shaft 95 and are adapted to engage spaced 70 portions of paper sheets of any desired width. When the press is being used for printing paper sheets which are comparatively narrow, it will be unnecessary to employ all of the vacuum drums 31 and means are therefore provided for render- 75

ing one or more of these drums inoperative at the will of the operator. For this purpose, the portions 97^a of the two outer suction blocks are provided with bores 97^c which are rotatably engaged by valve members 112, as shown particularly in Figs. 9 and 12. Each valve member is retained in its bore by a transverse pin 113 and it is provided at the other end with an enlarged head 112^a provided with a groove 112^b adapted for engagement by a screw driver or the like for the purpose of rotating the valve member to cause the angular passage 112^c formed therethrough to establish a connection between the complementary parts of the associated passages 97^b or to close that communication, as desired. The head 112^a of each valve member is provided with right-angularly disposed recesses 112^d, either of which may be engaged by a ball 114 mounted in a recess 97^e formed in the suction block, which recess also contains a coil spring 115 by which the ball is pressed into engagement with the recess in the valve member. In order to prevent the close contact of the paper sheet with the supporting plate 30^b from creating a suction effect which might interfere with the ready picking up of the paper sheet by the vacuum drums, the plate 30^b is preferably perforated at points below each of the suction passages 97^b, or throughout its area, by providing small openings 30^d each of which preferably diverges downwardly in order to prevent the clogging of these openings by dust or the like. The atmospheric pressure is thus permitted to act freely on each side of the paper sheet beneath the suction drums so that the sheet is readily picked up by the vacuum pressure established through the passages 97^b and the openings 30^d.

The supporting plate 30^b is preferably spaced from the lower portions of the drums 31 a distance somewhat greater than the thickness of any paper sheet which may pass through the press and, while a fixed spaced arrangement of the drums 31 and the supporting plate 30^b will permit the efficient handling of paper sheets having a considerable variation in thickness, it may be desirable, in some instances, to vary the spaced relation of the plate 30^b and the drums 31 according to the thickness of the paper sheets being used in the press and for this purpose the supporting plate 30^b is provided on its under side, as shown in Figs. 6, 7, 11 and 12, with a series of aligning blocks 117 each of which is adapted to be engaged by an eccentric portion 118^a of a shaft 118 which is journaled in bearing brackets 119 secured by studs 120 to the under side of the body portion of the table 30 which, in turn, is secured to the side frames 28. The shaft 118 is provided with a depending crank arm 121 having a pivotal connection with an adjusting rod 122 which slidably engages the hub 123^a of a bracket 123 attached to the adjacent side frame. The adjusting rod 122 may be reciprocated to turn the shaft 118 through the medium of the crank arm 121, thereby raising or lowering the supporting plate 30^b and adjusting the spaced relation of this plate and the lower portions of the drums 31. The adjusting rod 122 may be secured in adjusted position by a thumb screw 124 engaging the bracket 123 and the projecting portion of the rod 122 may be provided with graduations 125 for indicating the spaced relation of the plate 30^b and the drums 31, the face of the bracket 123 serving as the index mark.

For the purpose of imparting to the shaft 95 an intermittent rotary motion, each increment

consisting of a complete revolution, this shaft is provided at one end with a gear 130 which meshes with a gear 131 mounted to revolve on a short shaft 132 which has one end fixed in one side frame 28 and the other end secured in a bracket 133 which is secured to the side frame, as shown in Fig. 9. The gear 131 is provided with a relatively fixed ratchet disk 134 provided with a pair of diametrically opposed notches 134^a adapted to be engaged by a pawl 135. This pawl is pivoted on a pin 136 carried by an actuating member 137 which is in the form of a hub mounted on the shaft 132 with an outwardly projecting arm 137^a in which the pin 136 is fixed. The pawl 135 is provided with a tail portion 135^a and a coil spring 138, seated in a recess in the arm 137^a, bears against this tail portion to force the pawl 135 against the periphery of the ratchet member 134. The actuating member 137 is adapted to have an intermittent rotary motion, during each period of which the pawl 135 moves through an angle of 180 degrees, so that, upon each forward movement of the actuating member and the pawl, the ratchet member 134 is rotated a half revolution of the gear 131. The gear ratio between the gear 131 and the gear 130 is such that upon each half revolution of the gear 131, the gear 130 is rotated a complete revolution, at the end of which the shaft 95 and the vacuum drums 31 are arrested and remain stationary while the actuating member 137 reverses its movement to bring the pawl 135 into engagement with the next notch of the ratchet member 134.

The reciprocatory angular motion of the actuating member 137 is effected through a gear 140 keyed upon a hub of the actuating member and meshing with a gear 141 fixed upon a shaft 142 which is journaled in the side frame and in the bracket 133, as shown in Figs. 1, 2 and 3. The gear 141 is driven by a pinion 143 which is fixed upon another shaft 144 having bearings in the bracket 133 and in the adjacent side frame. The pinion 143 is driven by a gear sector 145 carried at the end of an actuating lever 146 which is pivotally mounted at 147 upon a bracket 148. The lever 146 has a depending arm 146^a provided with a roller 149 adapted to travel in the groove 150^a of a cam 150 which rotates continuously and, through the roller 149, imparts a reciprocatory motion to the lever 146, thus giving corresponding reciprocatory angular movements to each of the gears in the chain of gearing leading up to the actuating member 137. There is thus imparted to the vacuum drums 31 an intermittent rotary motion whereby these drums rotate continuously in the same direction and come to a stop at the end of each revolution with the forward aperture of the series of apertures 31^d in each drum located beneath one of the suction passages 97^b, as shown in Fig. 11, in readiness to pick up a paper sheet positioned against the removable stops 33.

The cam 150 is rotatably mounted upon the hub 151^a of a positioning member 151 which is in turn fixed upon a shaft 152 extending transversely of the press and having bearings in the side frames 28, as shown in Figs. 1 and 3. The shaft 152 has a large gear 153 secured thereon to mesh with a driving pinion 154 which is fixed upon the previously described shaft 71 so that the shaft 152 is rotated continuously during the operation of the driving motor. In order to adjust the angular position of the cam slot 150^a in the cam 150 to cause the initial opening 31^d in the periphery of each vacuum drum 31 to be

positioned beneath one of the suction passages 97^b, when the drums 31 come to rest at the end of each revolution thereof, the connection between the cam 150 and the adjusting member 151 is such as to permit angular adjustment of the cam. For this purpose, the adjusting member has a disk extending adjacent the face of the cam and provided with a series of elongated slots 151^b which are adapted to be engaged by 0 studs 155 which pass through the washers 156 and into threaded apertures 150^b formed in the cam. The cam may thus be adjusted angularly on the member 151 and then the studs 155 may be tightened to secure the cam in adjusted position. For the purpose of securing fine adjustments of the cam, the adjusting member 151 is preferably provided with a pair of spaced projecting ears 151^c which are threadedly engaged by adjusting screws 158 adapted to contact with 20 opposite sides of a lug 159 carried by the face of the cam. A graduated plate 160 is secured to the adjusting member 151 and the lug 159 carries an index mark adapted to show with respect to these graduations, the degree of angular adjustment 25 of the cam around the adjusting member. In this way, the cam 150 may be accurately positioned in order to cause the actuation of the vacuum drums 31 to begin at the proper intervals in the operation of the press and to cause the initial 30 aperture of each series of apertures 31^d to be properly located when the vacuum drums come to rest.

The hollow shaft 95 is connected at the end thereof adjacent the gear 130 with an elbow 165 which communicates with a vacuum tube 166. The elbow 165 is provided with a leather washer 167 which bears against the periphery of the shaft 95 and the chamber within this washer contains an annular collar 168 of leather or other packing material which bears against the adjacent face of the elbow so that a substantially fluid-tight connection is thus established between the stationary elbow and the rotating shaft 95. The vacuum tube 166 extends downwardly adjacent the vertical shaft 17, as shown in Fig. 1, and the lower end thereof communicates with an elbow 169 which is secured in a valve block 170 carried by the lower part of the side frame. This valve block has a transverse passage 170^a communicating with the elbow 169 and also with a vacuum pipe 171 which leads to the suction pump adapted to be continuously driven by an electric motor or the like during the operation of the press. The valve block 170 is provided with an upwardly extending bore 170^b which intersects the bore 170^a and which has slidably mounted therein a valve plug 172. At the upper end of this valve plug there is mounted a bracket 173 and a coil spring 174 is interposed between this bracket and the upper face of the block 170 so that the spring acts normally to elevate the plug and permit a free communication between the pipe 171 and the elbow 169. The bracket 173 carries a roller 175 arranged to bear upon the surface of a cam 176 which is secured on a shaft 177 rotatably mounted in a bracket 178 carried by the valve block 170. A sprocket gear 179 is secured on the shaft 178 adjacent to the cam 176 and this sprocket gear meshes with a sprocket chain 180 which passes around a sprocket gear 181 fixed upon the previously described shaft 152 so that during the operation of the press, the cam 176 is continuously driven and effects an intermittent downward movement of the valve plug 172 with 70 the result that the connection of the suction pipe

171 with the elbow 169 and the vacuum tube 166 is intermittently closed. The cam 176 is so positioned on the shaft 177 that the suction connection is closed by the valve plug 172 during those portions of the revolutions of the vacuum drums 31 in which the unperforated portions of the drums pass beneath the suction passages 97^b in the blocks 97.

The stop members 33 which engage the forward edge of each paper sheet 22 on the supporting plate 30^b, as shown in Fig. 11, preliminary to the picking up of the paper sheet by the vacuum drums 31, are carried by the arms 33^a which are positioned between the drums, as shown in Figs. 2 and 6, and which are provided with 10 split hubs 33^b adapted to be clamped on the previously described shaft 99 by means of clamping bolts or studs 185. With this arrangement, the rocking of the shaft 99 in its bearings will elevate the stop members 33 from the paper-engaging positions shown in Figs. 6 and 11 to the elevated position shown in Fig. 4, thus permitting the paper sheet to pass over the supporting plate 30^b until it engages the stops 35 on the cylinder 34, as shown in Fig. 12. This rocking movement 20 is effected by means of a crank arm 186, shown in Fig. 1, which is fixed on the end of the shaft 99 and which carries a roller 187 arranged to bear upon the peripheral surface of a cam 188 fixed upon the end of a shaft 189 which is journaled in the brackets 100. A coil spring 190 is connected to a pin 191 projecting from the end of the lever 186 and also to a stationary pin 192 fixed on the adjacent bracket 100, thus maintaining the roller 187 in engagement with the cam. 30 This cam has a substantial portion of its peripheral surface arranged concentrically with the axis of the shaft 189 and spaced some distance from said axis so that when this portion of the cam is in contact with the roller 187, as shown in 40 Fig. 1, the crank arm 186 is depressed, thereby causing the arms 33^a to be elevated, as shown in Fig. 4, to permit the movement of the paper sheet over the table under the influence of the vacuum drums 31. At the end of this stage of the operation, and after the rear edge of the sheet has passed onto the cylinder 34 from the supporting plate 30^b, the stops 33 are quickly depressed into the notches 30^c of the supporting plate as the roller 187 passes into engagement with the sharply inclined portion of the cam 188, the stops 33 remain in the positions shown in Figs. 6 and 11, while another sheet of paper travels over the table 30 and engages those stops, whereupon the sharply inclined portion of the cam 188 at the 50 other side of the axis of the cam causes the arms 33^a to be quickly elevated until they reach the position where they are retained in their elevated positions while the roller 187 is in engagement with the portion of the cam which is concentric with the cam axis. In this way, the continuously rotating shaft 189, which is actuated as hereinabove described, causes a periodic elevation of the stops 33 in the proper timed relation to the rotation of the vacuum drums 31 and the positioning of the stops 35 on the cylinder 34 in the proper location to receive the paper sheet.

As each paper sheet moves over the supporting plate 30^b, it is guided into engagement with the stops 35 on the cylinder by the guide fingers 31, 70 previously referred to. These guide fingers are carried by brackets 195 which have projecting ears 195^a engaged by screws 196 which may be adjusted to clamp these brackets upon a tubular shaft or sleeve 197 which is mounted to rock 75

about a shaft or axle 198 having its ends secured in the hangers 199, the ends of the shaft 198 being threaded for engagement by nuts 200, as shown in Figs. 2 and 7. The hangers 199 are 5 provided with split hubs 199^a which are secured together and clamped upon a sleeve or hollow shaft 202 which is mounted upon a shaft or axle 203 extending between and secured in the side frames 20. Each bracket 195 has a horizontally 10 projecting arm 195^b provided with an aperture which is engaged by a rod 205. These rods 205 are suspended from members 206 which are mounted upon the rod or shaft 207 extending between the side frames. Each rod 205 carries a 15 fixed collar 208 and a coil spring 209 which is positioned on the rod between the collar and the coacting arm 195^b, as illustrated in Fig. 7, so that when the brackets 195 are rocked about the shaft 198, the springs 209 are compressed by the upward movement of the arms 195^b. For the purpose of elevating the guide fingers 37, the hollow sleeve or shaft 197 has fixed thereon a crank arm 210, shown in Fig. 6, which carries at its upper and outer end a roller 211 adapted to coact 20 with the peripheral surface of a cam 212 fixed upon a shaft 213 which has bearings in the brackets 100. The cam 212 is so formed that after the forward edge of the paper sheet has been gripped by the gripping fingers 38 on the 25 cylinder 34, the lever 210 is actuated by the cam to rock the hollow shaft or sleeve 197, thereby elevating the stop fingers 37 to the position shown in Fig. 6 and compressing the springs 209. This elevation of the stop fingers 37 is maintained 30 while the roller 211 contacts with that portion of the cam 212 which is concentric with the axis of the shaft 213 and then the fingers 37 are again moved to the position shown in Fig. 7 as the roller 211 rides inwardly on the 35 sharply inclined portion of the cam under the influence of the springs 209.

The shaft 213 is provided at one end with a relatively fixed gear 215 which meshes with an idler gear 216 mounted to revolve about a stub 40 shaft 217 fixed in the adjacent bracket 100, as shown in Figs. 2, 4 and 6. The gear 217 meshes with a gear 218 fixed upon the previously described shaft 189 which carries the cam 188 for actuating the stops 33. The gear 218 is driven 45 through an idler gear 219 which is mounted to rotate on a stub shaft 220 carried by the adjacent bracket 100. The gear 219 is driven by a gear 221 fixed upon a shaft 222 which extends transversely of the machine with its ends journaled in the brackets 100. The gear 221 is driven 50 by a gear 223 mounted upon a stub shaft 224 carried by one of the side frames, as shown in Fig. 4. The gear 224 is in turn driven by a gear 225 fixed upon a horizontal shaft 226 which has 55 one end journaled in one of the side frames 20 and the other end journaled in a frame member 230 which is supported by rods 231 and 232 extending between the side frames, as shown in Fig. 3. The rod 232 is also supported adjacent 60 the frame member 231 by a member 233 which is supported upon a transverse frame member 234 secured to the side frames. This shaft 226 also has fixed thereon a sprocket gear 227, shown particularly in Fig. 3, which is driven by a sprocket chain 228. This sprocket chain passes around a sprocket gear 229 on the shaft 152 which has 65 previously been described as the shaft upon which the cam 150 is located. As heretofore explained, the shaft 152 is driven continuously when the 70 driving motor of the press is in operation and it

will be apparent that, through the connections which have just been described, all of the shafts 213, 189, 222 and 226 are also continuously driven for actuating the various parts of the mechanism which are connected thereto.

In addition to the mechanism heretofore described for transferring the paper sheets from the conveyor 21 and positioning them accurately against the stops 35 on the paper carrying cylinder 34, the present invention involves means 10 for positioning the paper sheets laterally on the table 30 so that the printed matter or the like subsequently placed upon the sheets will be located at the same distance from the edge of each sheet. This involves the movement of the 15 sheets 22 laterally on the table 30 while they are positioned against the stops 33, as shown in Fig. 6, and in order that the sheets may be moved laterally by pressure applied to the edges thereof, means are provided for buckling each sheet 20 downwardly before the lateral pressure is applied, thus giving the sheet greater stiffness to resist the lateral pressure. As shown particularly in Figs. 4, 6, 7 and 8, the shaft 222 has pivotally mounted thereon adjacent each side of the 25 machine a lever 235 each of which is provided with a downwardly inclined arm 235^a. The extremities of these arms are secured to the ends of a rod or shaft 236 upon which is mounted a sleeve or roller 237. When the levers 235 are 30 rocked downwardly about the shaft 222, the roller 237 is adapted to engage the upper surface of the paper sheet 22 and press it downwardly into the groove 30^c, of curved cross-section, which is formed in the upper face of the body portion of 35 the table 30, extending throughout the width of the table. There is thus formed a rib or buckle in the paper sheet which gives it sufficient resistance to permit it to be pushed over the table transversely of the press. It is desirable that the 40 roller 237 produce the required deflection in the paper sheet without exerting too much pressure thereon and in order that the position of the roller, when it is depressed as shown in Fig. 6, may be adjusted to accommodate various thicknesses of paper, means are provided for adjusting the levers 235 with respect to the devices by which they are actuated. For this purpose, a lever 240 is pivotally mounted on the shaft 222 adjacent each of the levers 235 and is connected 45 thereto so that when the lever 240 is rocked about the shaft, the adjacent lever 235 is also given a corresponding movement. Each lever 240 has an upwardly inclined arm 240^a carrying at its 50 end a roller 241 which is adapted to coact with the periphery of one of the cams 242 which are secured upon the previously described shaft 189 by which the movement of the stop members 33 is controlled. Each lever arm 240^a is connected 55 by a coil spring 243 with a stationary pin 244 positioned on the adjacent bracket 100 so that these springs normally rock the levers 235 and 240 upwardly about the shaft 222 and maintain the rollers 241 in engagement with the cams 242. The two levers 235 and 240 at each end of the 60 shaft 222 are connected by a stud 245 engaging a slot 235^b in the lever 235 and a threaded aperture in the lever 240, and the two levers are also connected by a stud 246 which threadedly engages the lever 240 and which has mounted thereon an 65 adjustable cam 247 seated in a U-shaped slot 235^c which is formed in the end of the lever 235. Upon loosening the studs 245 and 246, the cams 247 may be rotated for adjusting the relative angular positions of the connected levers 235 and 70 75

240, whereupon the studs may be tightened again to hold the parts in adjusted position. In this way, the extent to which the paper engaging roller 237 is depressed by the action of the cams 242 may be varied as desired.

The means for positioning a paper sheet laterally on the table 30 after a portion of the sheet has been depressed into the groove 30^c in the table by the operation of the roller 237, comprises a positioning bar 250 located in a rectangular groove 30^c formed in and extending transversely of the table 30, as shown particularly in Figs. 13 and 15. The length of the bar 250 is somewhat less than the width of the table to permit some adjustment of the bar laterally of the table and the bar carries a vertically extending positioning plate 251 which lies parallel to the direction of travel of the paper sheets and which is adapted to engage a lateral edge of the sheet so that when the bar 250 is momentarily moved transversely of the press, while the sheet is positioned against the stops 33, the longitudinal edge of the sheet engaged by the plate 251 is moved to a predetermined position which is assumed in turn by the longitudinal edge of every other sheet as the sheets pass through the press. The plate 251 is carried by a block 252 which is provided with an elongated slot 252^a adapted to be engaged by a stud 253 adapted to extend downwardly into any selected one of a series of threaded apertures 250^a which are formed in the positioning bar 250 for some distance inwardly from each end thereof. The block 252 may thus be located in any position within a considerable range for accommodating paper sheets of various widths. In order to obtain a finer adjustment of the position of the plate 251, this plate is connected with the block 252 by means of a pin 254 and a threaded stud 255 each of which engage horizontal apertures formed through the upper part of the block, as shown in Figs. 13 and 15, and the stud 255 is engaged by a nut 256 located in a recess 252^b, formed in the block, so that this nut may be rotated by the engagement of the fingers of the operator with the external knurled surface thereof for the purpose of adjusting the plate 251 longitudinally of the positioning bar 250. Each end of the positioning bar 250 is provided with a stop member 257 in the form of a bolt which threadedly engages a hole 250^b formed in the positioning bar. These bolts are secured in adjusted position by set screws 258 and their heads form stops which are adapted to engage the side frames 20 at the end of the groove 30^c for the purpose of limiting the movement of the bar 250 by the actuating mechanism hereinafter described. The positioning of the paper sheet on the table 30 is effected by moving the bar 250 to a predetermined extent in its groove 30^c, thereby pushing the paper sheet transversely of the table to a predetermined point, after which the bar 250 and the positioning plate 251 are returned to their initial positions. The positioning bar 250 is provided with holes 250^a adjacent both ends thereof so that the positioning plate 251 may be located on the bar adjacent either longitudinal edge of the sheet, which is desirable in order that after all of the sheets of a series have been passed through the press and printed matter placed on one side of each sheet, while positioning the sheets by the engagement therewith of the plate 251, the sheets may then be reversed and passed through the press again for placing printed matter on the other sides thereof, whereupon the plate

251 may be located at the other end of the bar 250 so that it will again engage the same edges of the sheet as were previously engaged by it during the preceding printing operation.

The mechanism for moving the positioning bar 250 is shown particularly in Figs. 3, 4, 13, 14 and 15, and it comprises an operating member 260 slidably mounted upon the rotating shaft 226 heretofore described and having a forwardly extending arm 260^a which is connected to the under side of the bar 250. This connection is established by a pin 261 secured in a plate 262 which is secured to the bar 250 by rivets 263. The plate 262 is located in an elongated slot 30^c formed in the bottom of the table 30 and the pin 261 extends downwardly to engage a hub 260^b which is formed at the end of the arm 260^a. In addition to being supported upon the rotating shaft 226, the operating member 260 is provided with a downwardly and rearwardly inclined arm 260^c which is provided at its end with a hub 260^d slidably mounted upon the rod 232 which extends between the side frames 20.

The movement of the operating member 260 transversely of the press is effected by a pair of similar cams 265 which are secured on the shaft 226 on opposite sides of the member 260 with their U-shaped projections 265^a extending inwardly toward each other, as shown in Fig. 13. The member 260 is provided with a roller 266 adapted to be engaged by one or the other of the cams 265 for moving the operating member 260 and the connected positioning bar 250 in one direction laterally of the press. Movement of the member 260 in the opposite direction is effected, and the engagement of the roller 266 with one of the cams 265 is maintained, by means of a coil spring 267 which is connected to the lower arm 260^c of the operating member and to one of the pins 268 which project downwardly from the rod 231. When the positioning plate 251 is located at the other end of the positioning bar 250, the coil spring 267 is reversed and connected to the other pin 268 and the operating member 260 is then actuated by the cam 265 which is shown as being out of engagement with the roller 266 in Fig. 13. In order that the position of the roller 266 may be adjusted to accommodate the actuation of the operating member 260 by either cam 265, the shaft 269 of this roller is mounted in an adjustable plate 270 which is of triangular shape, the apex thereof being secured to the end of the operating member 260 by means of a screw 271 and the lower part thereof being provided with an elongated curved slot 270^a which is engaged by a stud 272 entering a threaded hole in the operating member 260. This stud 272 may be employed to clamp the plate 270 either in the position shown in Figs. 13 and 14, in which the roller 266 is swung to a position where it is adapted to be actuated by the right-hand cam 265, but it may be employed to clamp the plate 270 after it has been swung to the left, as viewed in Figs. 13 and 14, whereby the roller 266 is swung into position to be actuated by the left-hand cam 265. In this way, the continuously rotating shaft 226 is utilized for causing the projection 265^a of one of the cams 265 to effect a periodic movement of the operating member 260 and the connected positioning bar 250 transversely of the press. The cams 265 are so positioned on the shaft 226 that this movement of the bar 250 and the corresponding movement of the paper sheet by the plate 251 occurs at the instant when the paper sheet is positioned against the stops 33 at the edge of 75

the table 30 and thus all of the paper sheets are positioned laterally of the press in the same manner before the stops 33 are elevated and the paper sheets are moved to the cylinder 34 by the operation of the vacuum drums 31.

From the foregoing description it will be apparent that the sheets of paper or other stock are moved in succession by the conveyor 21 onto the table 30 and that they slide over the table under the influence of the conveyor until arrested by the stops 33 which are then in the positions shown in Figs. 6 and 11. Immediately after each sheet 22 comes to rest against the stops 33, the roller 237 is depressed through the actuation of the levers 235, 240 by the cams 242. While a portion of the paper sheet is momentarily depressed within the groove 30^a formed in the table 30, one of the cams 265 upon the shaft 228 operates to move the member 260 transversely of the press and thereby actuate the bar 250 and plate 251 to move the sheet laterally to a predetermined point on the table. As soon as this has been accomplished, the stops 33 are elevated by the rocking of the shaft 99 which is effected by the cam 188 on the shaft 189. At this point in the operation of the cam 176, the shaft 177 assumes a position which permits a vacuum connection between the pipe 171 and the vacuum tube 166 to be opened so that a partial vacuum is then created in the hollow shaft 95 and in the passages of each of the vacuum blocks 97. At the same time, the pawl 135 drops into one of the notches 134 in the ratchet member 134 and causes a half revolution of the gear 131 and a corresponding complete revolution of the gear 130 and of the hollow shaft 95. The vacuum drums 31 turn through one complete revolution with the shaft 95 and during the early portion of this revolution, the suction openings 31^a of each vacuum drum are positioned successively above those successive portions of the paper sheet which are opposite the associated vacuum passage 97^b. Successive portions of the paper sheet are thus gripped by each rotating drum 31, by the action of atmospheric pressure forcing the paper sheet against the parts where suction is applied to the opposite side of the sheet, so that the sheet is thus positively fed from the table 30 until its forward edge is positioned against the stops 35 on the cylinder 34, as shown particularly in Fig. 12. By this time, the last suction opening 31^a in each vacuum drum will have reached a position opposite the associated vacuum passage 97^b and, as the drums continue to rotate, the lower end of each vacuum passage 97^b is closed by the unperforated portion of the drum and the valve plug 172, shown in Fig. 1, is then actuated by the came 176 to shut off the connection of the source of suction with the vacuum tube 166. At this stage, the gripping fingers 38 which have been elevated by the engagement of the roller 54 with the uppermost stationary cam 55, shown in Fig. 5, are moved to gripping position by the spring 59, with the result that the paper sheet is then gripped and withdrawn from the table by the rotation of the cylinder. During the movement of the paper sheet into engagement with the stops 35 on the cylinder 34, the forward edge of the sheet is guided by the fingers 37 which, at that stage of the operation, occupy the position shown in Fig. 4, but, as soon as the paper sheet has been gripped by the fingers 38, these guiding fingers 37 are elevated by the operation of the cam 212 so that as the paper sheet is being carried around the rotating cylinder 34, the guide

fingers 37 occupy the position shown in Fig. 6. The paper sheet is then carried around the cylinder 34 to receive a printed impression from the transfer cylinder 40, as heretofore explained, whereupon the paper sheet is taken off by the delivery cylinder 60 and carried to the stacking apparatus by the endless chain 64.

It will be apparent that the sheet transfer mechanism above described causes a positive and uniform movement of successive sheets from the paper supporting table to the paper carrying cylinder independently of any irregularities in the effective diameters of the feeding drums which may be caused by the accumulation of ink thereon from sheets passing through the press which have been printed on one side only. The sheets pass through a space between the table and the drums which is of such size that the particles of ink accumulating on the drums are not pressed onto the paper sheets and the regularity and uniformity of the feed is not disturbed. In prior devices in which the transfer of the paper sheets has been effected by friction rolls against which the paper sheets have been pressed by idler rolls, the ink which accumulates on the feed rolls is spread out by the pressure between the rolls, with the result that the sheets are smeared with ink as they are fed to the cylinder. As a result of this advantage, the present invention permits a more speedy operation of the press in color printing since it is possible to print the sheets with the second or succeeding colors of a series before the sheets have entirely dried following the first or preceding printing of another color and the time required for an entire printing operation is therefore greatly reduced.

Although one form of the invention has been shown and described by way of illustration and has been referred to as adapted for use in feeding paper sheets, it will be understood that it may be constructed in various other embodiments and may be employed in effecting the transfer of sheets of other material without departing from the scope of the appended claims.

I claim:

1. The combination in mechanism of the class described, of a cylinder adapted to carry a sheet of paper, paper positioning means having a normally stationary position, means for delivering a sheet of paper to said stationary positioning means, and angularly movable pneumatic means positively gripping said sheet for feeding said sheet to said cylinder after it has been positioned.

2. The combination in mechanism of the class described, of a cylinder adapted to carry a sheet of paper, paper positioning means having a normally stationary position, means for delivering a sheet of paper to said stationary positioning means, and rotary vacuum feeding means for transferring said sheet to said cylinder after it has been positioned.

3. The combination in mechanism of the class described, of a cylinder adapted to carry a sheet of paper, paper positioning means having a normally stationary position, means for delivering a sheet of paper to said positioning means, means for retracting said positioning means, and a rotary vacuum device for engaging said sheet and moving it to said cylinder.

4. The combination in mechanism of the class described, of a paper carrying cylinder having stops, means for delivering a paper sheet, positioning members adapted to engage the forward edge of said sheet, means for removing said members from engagement with said sheet, and

vacuum means for moving said sheet into engagement with said stops.

5. The combination in mechanism of the class described, of means for delivering a paper sheet 5 a rotatable cylinder having stops, means for rotating said cylinder, and movable vacuum feeding means adapted to grip said sheet and move it into engagement with said stops, said feeding means having a speed greater than the speed of 10 said stops.

6. The combination in mechanism of the class described, of vacuum feeding means, a separate support mounted in stationary position beneath said feeding means for holding a paper sheet 15 adjacent said feeding means, means for delivering a paper sheet to said support, normally stationary means against which said sheet is positioned by said delivering means, a cylinder, and means for actuating said vacuum feeding means 20 relatively to said support to move said sheet from said support to said cylinder.

7. The combination in mechanism of the class described, of a support, means for delivering a paper sheet to said support, positioning means 25 located normally in a stationary position in the path of travel of said sheet for engaging the forward edge of said sheet, a cylinder, means for removing said positioning means from the path of travel of said sheet, and rotary vacuum means 30 positioned above said support and said sheet for moving said sheet from said support to said cylinder.

8. The combination in mechanism of the class described, of a support, means for delivering a paper sheet to said support, positioning means 35 located in the path of travel of said sheet for engaging the forward edge of said sheet, a cylinder, means for removing said positioning means from the path of travel of said sheet, vacuum means 40 for moving said sheet from said support to said cylinder, and stops on said cylinder for engaging the forward edge of said sheet.

9. The combination in mechanism of the class described, of a support, means for delivering a paper sheet to said support, positioning means located in the path of travel of said sheet for engaging the forward edge of said sheet, a cylinder, means for removing said positioning means from the path of travel of said sheet, vacuum means 50 for moving said sheet from said support to said cylinder, stops on said cylinder for engaging the forward edge of said sheet, and gripping means for holding said sheet after it has engaged said stops.

55 10. The combination in mechanism of the class described, of a support, means for delivering a paper sheet to said support, positioning means located in the path of travel of said sheet for engaging the forward edge of said sheet, a cylinder, means for removing said positioning means from the path of travel of said sheet, vacuum means 60 for moving said sheet from said support to said cylinder, stops on said cylinder for engaging the forward edge of said sheet, and guide members 65 for directing the forward edge of said sheet into engagement with said stops.

11. The combination in mechanism of the class described, of a support, means for delivering a paper sheet to said support, positioning means 70 located in the path of travel of said sheet for engaging the forward edge of said sheet, a cylinder, means for removing said positioning means from the path of travel of said sheet, vacuum means 75 for moving said sheet from said support to said cylinder, stops on said cylinder for engaging the

forward edge of said sheet, guide members for directing the forward edge of said sheet into engagement with said stops, gripping means carried by said cylinder for holding said sheet, and means for withdrawing said guide members after 5 said sheet has been engaged by said gripping means.

12. The combination in mechanism of the class described, of a support, means for delivering paper sheets successively to said support, a stop adapted 10 to engage the forward edge of each sheet on said support, means for withdrawing said stop from the path of travel of said sheets after a sheet has been positioned thereby, and a rotatable vacuum device actuated when said stop is withdrawn for 15 moving said sheets successively from said support.

13. The combination in mechanism of the class described, of a support, means for delivering paper sheets successively to said support, a stop adapted 20 to engage the forward edge of each sheet on said support, means for withdrawing said stop from the path of travel of said sheets after a sheet has been positioned thereby, a rotatable vacuum device having a part adapted to cause said sheets 25 to adhere thereto, and means for periodically rotating said vacuum device for moving said sheets from said support at the times when said stop is withdrawn.

14. The combination in mechanism of the class described, of a support, means for delivering paper 30 sheets successively to said support, a stop adapted to engage the forward edge of each sheet on said support, means for withdrawing said stop from the path of travel of said sheets after a sheet has been positioned thereby, a series of spaced rotatable 35 vacuum devices having their peripheral portions movable adjacent to sheets positioned on said support, and means for rotating said vacuum devices periodically in timed relation with the withdrawal of said stop for moving said sheets 40 successively from said support.

15. The combination in mechanism of the class described, of a stationary support, means for delivering a paper sheet to said support, and means comprising a rotatable vacuum drum for moving 45 said sheet from said support.

16. The combination in mechanism of the class described, of a support, means for delivering a paper sheet to said support, and means comprising a plurality of rotatable vacuum drums spaced 50 apart transversely of said support for moving said sheet therefrom.

17. The combination in mechanism of the class described, of a support for a paper sheet, means for delivering a sheet to said support, a rotatable 55 drum mounted above said support with its periphery movable adjacent said sheet, said drum having a series of perforations in its peripheral portion, a source of suction, and means for establishing a connection between said source of 60 suction and each of said perforations in succession during the rotation of said drum.

18. The combination in mechanism of the class described, of a support for a paper sheet, a hollow shaft positioned above said support, a drum rotatable with said shaft with its periphery movable 65 adjacent said sheet, said drum having a series of perforations in its peripheral portion, a suction block positioned within said drum and having a passage communicating with the interior of said hollow shaft and adapted to register with said perforations successively, means for rotating said shaft, and means for connecting said shaft with a source of suction. 70

19. The combination in mechanism of the class 75

- described, of a support for a paper sheet, a hollow shaft positioned above said support, a series of drums mounted on and spaced apart along said shaft, said drums each having a perforated peripheral portion movable adjacent to said sheet, a series of suction blocks carried by said shaft, each of said suction blocks being positioned adjacent one of said drums and having a vacuum passage communicating with the interior of said shaft and adapted to register successively with the perforations in the adjacent drum, and means for effecting periodic complete rotations of said shaft.
20. The combination in mechanism of the class described, of a support for a paper sheet, a hollow shaft positioned above said support, a series of drums mounted on and spaced apart along said shaft, said drums each having a perforated peripheral portion movable adjacent to said sheet, a series of suction blocks carried by said shaft, each of said suction blocks being positioned adjacent one of said drums and having a vacuum passage communicating with the interior of said shaft and adapted to register successively with the perforations in the adjacent drum, a stop for engaging the forward edge of a paper sheet to position it on said support, means for withdrawing said stop after a sheet has been positioned thereby, and means for rotating said shaft each time said stop is withdrawn.
30. 21. The combination in mechanism of the class described, of a support for a paper sheet, a hollow shaft positioned above said support, a series of drums mounted on and spaced apart along said shaft, said drums each having a perforated peripheral portion movable adjacent to said sheet, a series of suction blocks carried by said shaft, each of said suction blocks being positioned adjacent one of said drums and having a vacuum passage communicating with the interior of said shaft and adapted to register successively with the perforations in the adjacent drum, means for effecting periodic complete rotations of said shaft, and means for rendering one of said drums inoperative for moving said paper sheet.
40. 22. The combination in mechanism of the class described, of a support for a paper sheet, a hollow shaft positioned above said support, a series of drums mounted on and spaced apart along said shaft, said drums each having a perforated peripheral portion movable adjacent to said sheet, a series of suction blocks carried by said shaft, each of said suction blocks being positioned adjacent one of said drums and having a vacuum passage communicating with the interior of said shaft and adapted to register successively with the perforations in the adjacent drum, means for effecting periodic complete rotations of said shaft, and valve mechanism associated with certain of said suction blocks for closing the suction passages therein.
50. 23. The combination in mechanism of the class described, of a support for a paper sheet, a hollow shaft mounted above said support, a rotatable vacuum drum carried by said shaft and comprising a radial disk having an annular transverse flange, said flange being provided with a series of perforations extending throughout a portion of its periphery, a suction block carried by said shaft and having a passage communicating with the interior of said shaft and extending downwardly with its mouth positioned above said sheet, the mouth of said passage being adapted to register with said perforations in succession during the rotation of said drum, means for connecting said
55. shaft with a source of suction, and means for rotating said shaft.
24. The combination in mechanism of the class described, of a support for a paper sheet, a hollow shaft mounted above said support, a rotatable vacuum drum carried by said shaft and comprising a radial disk having an annular transverse flange, said flange being provided with a series of perforations extending throughout a portion of its periphery, a suction block carried by said shaft and having a passage communicating with the interior of said shaft and extending downwardly with its mouth positioned above said sheet, the mouth of said passage being adapted to register with said perforations in succession during the rotation of said drum, means for connecting said shaft with a source of suction, and means for rotating said shaft.
60. 25. The combination in mechanism of the class described, of a support, means for delivering paper sheets successively to said support, a stop adapted to engage the forward edge of each sheet on said support, means for withdrawing said stop from the path of travel of said sheets after a sheet has been positioned thereby, a rotatable vacuum device actuated when said stop is withdrawn for moving said sheets successively from said support, and means for automatically connecting said vacuum device with a source of suction when its rotation begins.
65. 26. The combination in mechanism of the class described, of a support, means for delivering sheets successively to said support, a rotatable vacuum device for moving said sheets successively from said support, means for rotating said device, and means comprising a brake for bringing said device to rest at the end of each rotation.
70. 27. The combination in mechanism of the class described, of a support, means for delivering paper sheets to said support, a rotatable vacuum device for moving said sheets successively from said support, a source of suction, means for intermittently rotating said vacuum device, and means actuated during each rotation of said device for connecting said device with said source of suction.
75. 28. The combination in mechanism of the class described, of a support, means for delivering sheets successively to said support, a vacuum device for moving said sheets successively from said support, an actuating member having a reciprocating motion, and means actuated upon each forward motion of each actuating member for imparting a complete rotation to said vacuum device.
80. 29. The combination in mechanism of the class described, of a support, means for delivering sheets successively to said support, a vacuum device for moving said sheets successively from said support, an actuating member having a reciprocating motion, means actuated upon each forward motion of each actuating member for imparting a complete rotation to said vacuum device, and a brake associated with said vacuum device for bringing it to rest at the end of each rotation thereof.
85. 30. The combination in mechanism of the class described, of a support, means for delivering sheets successively to said support, a vacuum device for moving said sheets successively from said support, an actuating member having a reciprocating motion, means actuated upon each forward motion of each actuating member for imparting a complete rotation to said vacuum device.

device, and means actuated in unison with the rotation of said device for connecting said device with a source of suction.

31. The combination in mechanism of the class described, of a perforated support, a rotary vacuum device having a series of perforations adapted to engage successively a sheet positioned in direct contact with said support, a source of suction, and means adapted to establish a connection between said source of suction and said perforations in succession during the rotation of said device.

32. The combination in mechanism of the class described, of a support having a plurality of small holes therein, a rotary vacuum device located above said support having a series of perforations adapted to engage successively a sheet positioned on said support in direct contact therewith, a source of suction, and means adapted to establish a connection between said source of suction and said perforations in succession during the rotation of said device.

33. The combination in mechanism of the class described, of a sheet support, a rotary vacuum drum adapted to deliver a sheet from said support, said drum having a series of perforations extending through a portion of its periphery for engagements successively with a sheet positioned on said support, an actuating member having a reciprocating motion, means operated by said actuating member for imparting intermittent rotations to said drum with a period of rest at the end of each rotation, means for driving said actuating member, and means associated with said driving means for varying the positions of said perforations in said drum when said drum is at rest.

34. The combination in mechanism of the class described, of a support, means for delivering paper sheets successively to said support, a stop adapted to engage the forward edge of each sheet on said support, means for withdrawing said stop from the path of travel of said sheets after said sheet has been positioned thereby, a rotatable cylinder having a stop thereon, and a rotatable vacuum device actuated when said first named stop is withdrawn for moving said sheets successively from said support and positioning them successively against said stop on said cylinder.

35. The combination in mechanism of the class described, of a support, means for delivering paper sheets successively to said support, a stop adapted to engage the forward edge of each sheet on said support, means for withdrawing said stop from the path of travel of said sheets after said sheet has been positioned thereby, a rotatable cylinder having a stop thereon, a rotatable vacuum device actuated when said first named stop is withdrawn for moving said sheets successively from said support and positioning them successively against said stop on said cylinder, means for rotating said cylinder, and means for actuating said vacuum device to give each sheet a speed of travel greater than the speed of said stop on said cylinder.

36. The combination in apparatus of the class described, of a support, means for moving said sheets in succession onto said support, a rotatable cylinder having stops at its periphery, movable grippers mounted on said cylinder, a vacuum feeding device for engaging each sheet on said support and positively moving it against said stops on said cylinder, and means for actuating said grippers to engage each sheet and hold it

on said cylinder before said sheet is released by said vacuum feeding device.

37. The combination in apparatus of the class described, of a frame, a hollow shaft journaled in said frame, a series of drums mounted on said shaft, means for rotating said shaft, means for connecting the interior of said shaft with a source of suction, a second shaft mounted on said first named shaft, and a series of suction blocks each rotatably engaged by both of said shafts and each located adjacent one of said drums, each of said suction blocks having a passage communicating with the interior of said shaft, each of said drums having a series of peripheral openings adapted to register with said passage in the adjacent suction block, said shaft having a series of openings each adapted to communicate with one of said passages in a certain angular position of said shaft.

38. The combination in apparatus of the class described, of a frame, a hollow shaft journaled in said frame, a series of drums mounted on said shaft, means for rotating said shaft, means for connecting the interior of said shaft with a source of suction, a second shaft mounted on said first named shaft, a series of suction blocks each rotatably engaged by both of said shafts and each located adjacent one of said drums, each of said suction blocks having a passage communicating with the interior of said shaft, each of said drums having a series of peripheral openings adapted to register with said passage in the adjacent suction block, said shaft having a series of openings each adapted to communicate with one of said passages in a certain angular position of said shaft, a paper support mounted adjacent said drums, means for moving paper sheets onto said support, a series of paper stops mounted on said second named shaft and having parts adapted to engage the forward edge of each sheet on said support, and means for actuating said second named shaft to remove said stops from the path of travel of said sheets.

39. The combination in apparatus of the class described, of a sheet support, a rotatable feeding device mounted adjacent said support, a continuously rotating driving shaft, a cam mounted on said shaft, an operating member having a reciprocating motion imparted thereto by said cam, an actuating member having a reciprocating angular motion imparted thereto by said operating member, a ratchet wheel mounted for rotation opposite said actuating member, a pawl carried by said actuating member and adapted to engage successive teeth of said ratchet wheel upon successive reciprocating movements thereof, and means actuated by said ratchet wheel for imparting successive complete rotations to said rotary feeding device.

40. The combination in apparatus of the class described, of a sheet support, a rotatable feeding device mounted adjacent said support, a continuously rotating driving shaft, a cam mounted on said shaft, an operating member having a reciprocating motion imparted thereto by said cam, an actuating member having a reciprocating angular motion imparted thereto by said operating member, a ratchet wheel mounted for rotation opposite said actuating member, a pawl carried by said actuating member and adapted to engage successive teeth of said ratchet wheel upon successive reciprocating movements thereof, means actuated by said ratchet wheel for imparting successive complete rotations to said rotary

feeding device, and means for adjusting the angular position of said cam on said driving shaft.

41. The combination in mechanism of the class described, of a plate for supporting a single paper sheet, a paper feeding device movable above said plate for feeding paper sheets successively therefrom, and means for adjusting said plate toward and from said feeding device.

42. The combination in mechanism of the class described, of a plate for supporting a single paper sheet, a rotatable vacuum device mounted above said plate and adapted to pick up a single paper sheet positioned thereon, and means for adjusting the spaced relation of said vacuum device and said plate.

43. The combination in mechanism of the class described, of a plate for supporting a paper sheet, a rotatable vacuum device mounted above said plate and adapted to pick up a paper sheet positioned thereon, and a rotatable member mounted beneath said plate and having an eccentric portion adapted to effect movement of said plate with respect to said vacuum device.

44. The combination in mechanism of the class described, of a plate for supporting a paper sheet, a rotatable vacuum device mounted above said plate and adapted to pick up a paper sheet positioned thereon, a rotatable member mounted beneath said plate and having an eccentric portion adapted to effect movement of said plate with respect to said vacuum device, and graduated means for indicating the spaced relation of said vacuum device and said plate.

45. The combination in apparatus of the class described, of a sheet supporting table, means for moving a sheet on said table, a positioning member movable transversely of said table, a positioning plate reversible on said positioning member to engage either lateral edge of said sheet, an actuating member connected to said positioning member, a rotatable shaft, a pair of cams mounted on said shaft on opposite sides of said actuating member, and an adjustable roller carried by said actuating member for engaging and permitting the operation of said actuating member by either of said cams.

46. The combination in mechanism of the class described, of a cylinder adapted to carry a sheet of paper, paper positioning means mounted in a stationary position in advance of said cylinder, means for delivering single sheets of paper successively to said positioning means, and a rotary vacuum device for engaging each sheet and mov-

ing it to said cylinder after it has been positioned.

47. The combination in mechanism of the class described, of a cylinder adapted to carry a sheet of paper, paper positioning means mounted in a stationary position in advance of said cylinder, means for delivering single sheets of paper successively to said positioning means, means for moving said positioning means out of the path of movement of the positioned sheet, and rotary vacuum means operative thereafter for moving the positioned sheet to said cylinder.

48. The combination in mechanism of the class described, of vacuum feeding means, a stationary support for holding a paper sheet adjacent said feeding means, means for delivering a paper sheet to said support, a cylinder, and means for actuating said vacuum feeding means to move said sheet entirely thereby from said support to said cylinder.

49. The combination in mechanism of the class described, of a stationary paper support, means for delivering a paper sheet to said support, a cylinder, vacuum means located on the side of said sheet opposite said support for moving said sheet from said support to said cylinder, positioning means located in the path of travel of said sheet and mounted independently of said vacuum means for engaging the forward edge of said sheet, and means for removing said positioning means from the path of travel of said sheet to permit movement of said sheet by said vacuum means to said cylinder.

50. The combination in mechanism of the class described, of a stationary support adapted to support a single sheet of paper, means for delivering sheets of paper in succession to said support, a cylinder, and vacuum feeding means movable with respect to and in proximity to said support for feeding a sheet therefrom to said cylinder, said support and said vacuum feeding means being located on opposite sides of the sheet.

51. The combination in mechanism of the class described, of a stationary support adapted to support a single sheet of paper, means for delivering sheets of paper in succession to said support, a cylinder, vacuum feeding means movable in proximity to said support for feeding a sheet therefrom to said cylinder, and stops carried by said cylinder for positioning the forward edge of each sheet on said cylinder.

ALEXANDER T. KOPPE.
